UNITED STATES PATENT OFFICE.

WILLIAM P. STANHOPE, OF CINCINNATI, OHIO, ASSIGNOR TO THE BALDWIN COMPANY,
OF CINCINNATI, OHIO.

VALVE-FACING.

1,260,248.

Specification of Letters Patent. Patented Mar. 19, 1918.

Application filed September 29, 1917. Serial No. 194,059.

To all whom it may concern:

Be it known that I, WILLIAM P. STANHOPE, a citizen of the United States, and residing at Cincinnati, in the county of

5 Hamilton and State of Ohio, have invented certain new and useful Improvements in Valve-Facings, of which the following is a specification.

In the application of Robert A. Gally, 10 #186,224, is shown an improved facing and collar of a valve. The present application is an improvement in the attachment of such a facing to the valve disk.

In the drawings Figure 1 is a plan view, 15 and Fig. 2 an elevation of a rod and valve with the facing of the valve fastened in the improved manner, the facing only being in section.

The valve disk 1 of stiff material has a 20 facing 2 of soft and flexible material, as "skiver pneumatic" leather laid freely across the entire under face of the disk 1 and brought over the edge of the disk and turned in on the upper face of the disk and attached 25 to the disk by any suitable adhesive, as French varnish. The leather facing 2 has a decided tendency to spring away from the upper face of the disk 1, especially when the adhesion is slow to make, as on a metal 30 disk, as brass, and if not strongly adhered is likely to come loose after a time. This can be avoided by a scoring in the turned over flat part of the leather facing 2, said scoring 3 extending around the entire valve 35 on a line between the edge of the valve and the inner edge of the turned over part of the facing leather. This scoring 3 does several things:—works out any of the wrinkles occasioned by the turning over and inwardly 40 of the leather facing. The score line stiffens the turned over leather into a ring of which all parts help each other to remain in place. When the scoring is made at the time of

joining the facing to the disk it causes a forcing of an extra quantity of the adhesive 45 into two rings, one immediately at each side of the scoring, thus gaining an extra adhesion and stiffening of the leather.

Either a round, oval or polygonal or other form of valve may be made with the present 50 improved scoring of its facing.

What I claim as my invention is:—

1. A valve and a flexible facing extended over one face of the said valve and around the edge of the said valve and inwardly over 55 and adhesively attached to the opposite face of the said valve, and a scored depression extended into the said inwardly extended part of the said facing and around the said part of the said facing.

2. A valve and a flexible facing extended over one face of the said valve and around the edge of the said valve and inwardly over 60 and adhesively attached to the opposite face of the said valve, and a scored depression 65 extended into the said inwardly extended part of the said facing and around the said part of the said facing, and the said inwardly extended part of the said facing having a raised part immediately adjacent the 70 said scoring.

3. A valve and a flexible facing extended over one face of the said valve and around the edge of the said valve and inwardly over 75 and adhesively attached to the opposite face of the said valve, and a scored depression extended into the said inwardly extended part of the said facing and around the said part of the said facing, and the said inwardly extended part of the said facing 80 having two raised parts immediately adjacent the said scoring.

WM. P. STANHOPE.
